UNITED STATES PATENT OFFICE.

SHELBY N. GRIFFITH, OF MONONGAHELA, PENNSYLVANIA.

COMBINATION ELECTRIC PLUG AND SWITCH.

Application filed October 18, 1923, Serial No. 669,381. Renewed November 1, 1927.

This invention relates to improvements in electrical connections.

The primary object of this invention is the provision of improvements in attachment plugs of electrical apparatus, embodying a novel switch structure which may be used in conjunction therewith.

A further object of this invention is the provision of a novel switch apparatus which may be used as a part of electrical attachment sockets and plugs, being of a relatively simple nature and cooperating in compact and effective manner with the conventional socket and plug attachment parts.

15 A further object of this invention is the provision of an attachment socket which embodies a switch mechanism; the attachment socket being preferably that type which is used in connection with electric wires, which 20 are connected to the terminals thereof, and providing a socket for the reception of the contacts of an electrical appliance, such as an electric iron, toaster, stove, or the like. With such socket it will be at all times convenient 25 for a person to regulate the flow of current to the electrical appliance being heated, without the necessity of resort to remote switches.

Other objects and advantages of this invention will be apparent during the course of 30 the following detailed description.

In the accompanying drawings, forming a part of this specification, and wherein similar reference characters designate corresponding parts throughout the several views.

35 Figure 1 is a longitudinal cross sectional view taken through the preferred form of the invention, showing more particularly the application of the principle of this invention to an attachment socket.

40 Fig. 2 is an end elevation of the improved socket, showing the construction thereof.

Fig. 3 is an opposite end view of the improved attachment socket.

Fig. 4 is a cross sectional view taken substantially on the line 4—4 of Figure 1.

Fig. 5 is a perspective view of a novel type of contact member used in the improved attachment.

Fig. 6 is a longitudinal cross sectional view taken through an attachment plug, showing the application of the principle of this invention thereto.

Fig. 7 is an end view of the inserting body portion of the improved plug illustrated in 55 Figure 6.

Figs. 8 and 9 are cross sectional views

taken on their respective lines in Figure 6 of the drawings.

Fig. 10 is a novel contact member used in connection with the plug illustrated in Figure 6.

In the drawings, wherein for the purpose of illustration are shown electrical connections of different types to which the principle of this invention may be applied, the letter A may generally designate an attachment socket which may include the socket body portion F, and binding terminal carrying portion H. The attachment plug K see Figure 6 to which the principle of this invention is applied may include the inserting body portion L, and the binding terminal carrying portion M.

Referring to the construction of the attachment socket A, the socket portion proper or body portion F thereof is preferably split longitudinally in accordance with the well known construction, and includes the complementary sections 15 and 16 which may be secured together in detachable relation by means of bolts or screw devices 17, which extend transversely therethrough. The forward portion of the body F, as provided by the sections 15 and 16 thereof, is flattened, and provides the openings 19 and 20, within which the reinforcing or protecting metal sleeves 21 are mounted to provide socket openings for the reception of contacts. The socket openings of the sections 15 and 16 are so grooved in the facing or contacting surfaces of said sections 15 and 16, as to permit the ready embedding of the metal sleeves 21 therein when the sections are connected by the elements 17. The rear portion of the body F is substantially cylindrical, tapering to this shape from the flattened forward shape of the body portion F, to provide a chamber 25 therein, which is substantially one-half the length of the body portion F, extending to the socket openings 19 and 20, and being in communication

90 with the chamber 25. The chamber 25 is of novel formation, preferably being of greatest diameter at its communication with the socket openings 19 and 20, and tapering in diminishing diameter for outlet at the rear end or face 27 of the body F. The facing surfaces of the sections 15 and 16, are of course, similarly grooved to provide the chamber 25 as defined.

100 The binding terminal carrying portion H is of insulation material, as are also the sec-

110

tions 15 and 16 of the body portion F. It is novel construction, preferably including a forward end 30 of greatest diameter, which is to be disposed within the greatest diametered portion of the chamber 25. The portion H from the forward end 30 gradually decreases in diameter to a neck portion 31 which extends through the restricted area of the chamber 25, and has a head or knob portion 32 overlying the exterior end face 27 of the body portion F, substantially as is illustrated in Figure 1. Conducting wires 33 and 34 are led into the attachment socket A through ways 35 and 36 respectively provided longitudinally through the carrying portion H. These wires 33 and 34 are preferably respectively connected to contacts 38 and 39 which are fixedly secured within the terminal carrying portion H and are of identical construction. Arcuate recesses 40 and 41 are provided inwardly of the inside end face of the terminal carrying portion H, which are sufficiently deep to receive the contacts 38 and 39 therein. These recesses 40 and 41 are preferably arcuate, each extending for an arcuation of approximately 90°, struck from the axis of the portion H as a center.

Referring more particularly to a type of pivotal connection of the terminal carrying portion H within the body F, a pivot screw or member 44 may be provided, having its screw threaded end 45 secured within the portion H inwardly from the inside face thereof, and arranged axially with the portion H. The smooth shank portion 46 of the member 44 is pivotally mounted within a suitable opening provided by placing grooves in the sections 15 and 16 of the body F, and which opening provides a bearing for the shank 46, so that the portion H may rotate thereabout as an axis.

Referring more particularly to the contacts 38 and 39, the same are of identical construction, each being constructed as shown in Figure 5 and including an attaching flange 47, provided with an aperture 48 therein to receive a screw element 49 by means of which the terminals 38 and 39 may respectively be connected to an end of the recesses 40 and 41 to extend therein. Each of these contacts furthermore includes a pair of spring arms 50 and 51, which may be in spaced relation, and are preferably 55 arcuated. These spring arms 50 and 51 are offset from the plane of the attaching flange 47, and lie wholly within the recesses 40 and 41. These contacts 50 and 51 when disposed within their recesses are preferably arranged concentrically therewith and have the free ends of the same in facing relation with the major length of said recesses 40 and 41. Upon oscillative movement of the binding terminal carrying member H the contacts 38 and 39 may respectively be moved into

or out of registering relation with the socket openings 19 and 20. A suitable attaching flange 52 is of course laterally struck from each of the contacts 38 and 39, preferably from the arm portion 51 thereof, substantially as is illustrated in Figure 5, and which is provided with an aperture 53 therein to receive a set screw by means of which the conducting wires 33 and 34 may be attached to the contacts 38 and 39. 70 75

In connection with the attachment of the attachment connector A to an appliance R, it is preferred that said appliance R be provided with special contacts or prongs 55 and 56. These prongs or contacts 55 and 56 80 may be attached in any suitable manner 57 to the frame 58 of the appliance R, depending upon the character of the appliance R, whether the same is a stove, iron, toaster, or the like. Each of the prongs 55 and 56 85 preferably include the cylinder portion 59 adapted to be received within the socket openings 19 or 20, and a forwardly extending preferably flat or arcuate portion 60, which, when the connector A receives the prongs 55 and 56 extend into the chamber 25 thereof. The forwardly extending ends 60 of the contacts or prongs 55 and 56 respectively extend into the recesses 40 and 41 of the portion H. Upon pivotal movement of the 90 portion H within the body portion F, the fingers 50 and 51 of the contacts 38 and 39 may be selectively placed into or out of engagement with the prongs 60. This provides a switch structure or circuit maker and 100 breaker, so that the appliance R may be placed in or out of electrical connection with the wires 33 and 34, in facile manner. It is apparent, that by merely turning the terminal carrying portion H, at the knob 105 portion 32, that an operator may conveniently place the appliance R in or out of electrical connection with the terminal wires, without the necessity of detaching the socket device A from the prongs 55 and 56, as is 110 now the custom.

The principle of this invention as applied to the attachment plug K, see Figure 6, contemplates the provision of the inserting portion L, which is preferably of two part construction, including the main insulation support portion 71, which at its inserting end is preferably provided with the threaded contact shell 70 of metal. Inwardly of the face or surface 72 at the opposite end of the inserting face portion 71, a cylindrical shaped chamber 73 is provided, which rotatably receives therein a section 74 of the inserting portion L. The section 74 is of substantially cylindrical formation and of insulation material. The section 74 is preferably provided with an inwardly extending annular guide flange 75, which cooperates within an annular groove 76 provided at the bottom of the chamber 73. In this position the outer 120 125 130

- face of the section 74 lies flush with the face 72 of the body 71. A pivoting screw 77 is preferably provided, axially disposed through the section 74, and rotatably receiving the section 74 thereon; the screw threaded end of the pivoting screw 77 being affixed in the section 71 so as to connect the sections 71 and 74 to permit relative rotational movement thereof.
- 10 Within the body section 71 an annular pocket 80 is provided, just above the chamber 73, which is adapted to receive portions of contacts of the cap or binding terminal carrying portion M, as will be subsequently described. At the extreme inserting end of the body 71 passageways 82 and 83 are preferably provided, which communicate with the annular pocket 80 and outlet upon the forward face 84 of the inserting portion L.
- 20 Contacts 86 and 87 of identical formation are respectively disposed in the passageways 82 and 83. The contact 86 is adapted for electric conducting connection to the contact shell 70, while the contacts 87 is connected to a terminal 90 at the extreme inserting end of the plug K. Each of the contacts 86 and 87 is constructed as shown in Figure 10 and preferably includes an attaching portion 93 having an aperture 94 in the free end thereof to permit its connection to the body portion 71 of the inserting end portion L; resilient arms 95 and 96 being integrally connected with the attaching part 93 and extending in spaced relation within the passageways of the inserting body portion 71. At their free ends the arms 95 and 96 are provided with the laterally extending and relatively outturned guide flanges 97 which preferably extend into the annular pocket 80 of the inserting portion L.
- 30 Referring to the binding terminal carrying portion M, the same is of conventional construction, including the insulating body 100, which at its inside face provides a pocket 101 within which the contact terminals 102 and 103 are secured, as by set screws 104. The axial passageway 106 is provided, through which the conducting wires (not shown) may extend for attachment to the contacts 102 and 103, as by the set screws 105. The contacts 102 and 103 provide relatively long inserting shanks, which are adapted for respective extension through passageways 109 and 110 provided in the movable section 74 of the inserting portion L; said contacts 102 and 103 being sufficiently long to extend into the pocket 80 of the inserting portion L for respective co-operation with the contacts 86 and 87.
- 40 It must be understood that it is preferred that the portions L and M of the plug K be of a detachable nature. Notwithstanding this, means is provided within the plug structure K to insure the thoroughly coupled relation of the plug portions L and M in-
- dependent of the positioning of the contacts 102 and 103 with respect to their co-operating contacts 86 and 87 respectively. This means preferably includes the provision of a pair of resilient clamping arms 111 and 112 in each of the passageways 109 and 110, which are right angled at their forward ends, and connected by appropriate screws to the section 74. The free ends of the arms 111 and 112, are preferably relatively outturned adjacent the face 72 of the inserting portion L, to permit the easy insertion of the contacts 102 and 103 therein. It is to be observed that the attaching end 113 of the arms 111 in each of the passageways 109 and 110, is provided with an opening therethrough, through which the contacts 102 and 103 may be easily slid.
- 50 Referring to the operation of the invention, the application of the plug K in an appropriate socket is well understood. However, when performing as a switch, to place the wires which are carried by the portion M in conducting relation with the terminals of a socket, the contacts 102 and 103 are firmly coupled by the arms 111 and 112 thru the inserting portion L of the plug K so that the free ends of said contacts 102 and 103 extend into the pocket 80 and are in engagement with the contacts 86 and 87, between the arms 95 and 96 of each of said contacts 86 and 87, and substantially as is illustrated in Figure 6 of the drawings. However, when it is desired to disconnect the electric circuit it is merely necessary for the operator to manually turn the cap portion or terminal carrying portion M of the plug K, for an angle of approximately 90°. This operation will have the effect of drawing the ends of the contacts 102 and 103 from the spring arms of the contacts 86 and 87 respectively to break the circuit. This circuit breaking operation is performed while the parts L and M of the plug K are fully coupled. This coupling is primarily insured by reason of the gripping action of the spring arms 111 and 112 on the contacts 102 and 103; it of course being understood that the section 74 pivotally moves within the pocket 73 provided therefor and relative to the portion 71 of the inserting portion L.
- 60 Means may be provided upon the connector to determine the "on" and "off" positions of the switch structure therein. This means may include delineations 120 provided on the body portion of the unit, and an indicator mark 121 located on the movable portion of the same.
- 70 From the foregoing description of this invention it is apparent that a novel type of connector has been provided for electrical apparatus, which is extremely novel in that the provision of a switch structure is provided therefor. The attachment plug or socket retains much of the conventional

characteristics thereof, notwithstanding the novel utilization of the switch equipment in connection therewith.

Various changes in the shape, size, and arrangement of parts may be made to the form of invention herein shown and described, without departing from the spirit of this invention or the scope of the claims.

I claim:

- 10 1. An attachment plug comprising a body of insulating material having a pocket therein open at one end of the body and terminal receiving passages leading from the inner end of the pocket through the other end of the body, a block rotatably fitting in said pocket and having longitudinally extending wire receiving passages communicating at their inner ends with recesses extending circumferentially of the inner end of said block and each having a shoulder portion at the end communicating with its cooperating passage, and gripping terminals in the recesses of said block and each formed of resilient material and having a flange secured upon the shoulders at the end of the recess and gripping arms extending longitudinally of the recess whereby blade portions of terminals passing through the passages of said body may be gripped between the gripping arms when the block is rotated in the body, one of the gripping arms of each gripping terminal having a tongue struck therefrom and having fastener means carried thereby for engagement with a feed wire.
- 15 2. An attachment plug comprising a body of insulating material having a pocket leading from one end and passages leading from its other end and communicating with the pocket, a block of insulating material rotatable in the pocket and having longitudinally extending feed wire passages and its inner end provided with arcuate recesses each communicating at one end with a wire passage, terminals secured in the last mentioned ends of said recesses and each having a base portion anchored to the block and resilient arms extending from the base portion circumferentially of the block whereby terminal members extending
- 20 through the passages of said body into the

recesses of the block may be gripped between the arms when the block is rotated, and means for connecting feed wires with the terminals secured in the recesses of the block.

3. An electric appliance of the class described comprising a socket portion of two part construction split longitudinally and grooved in the facing surfaces thereof to provide a pocket which terminates intermediate the ends of the socket portion and outlets at one of the ends of the socket portion, said pocket adjacent the bottom thereof being of largest cross section and being of less and restricted cross section at its outlet at the end of said socket portion, and a movable switch portion mounted in the pocket of said socket portion having an enlarged inner end seating in the enlarged portion of the pocket and extending through the restricted portion of the pocket to exteriorly of the socket portion for rotation in said pocket, and wire connecting contacts, carried by the socket portion extending into said pocket, and by the switch portion, said wire connecting contacts of the socket portion and switch portion being adapted for engagement and disengagement as the switch portion is rotated in the pocket of the socket portion.

4. An attachment plug comprising a body, having a pocket, a block rotatable in the pocket, said body having passages leading from the pocket through one end of the body, terminals in said passages each U-shaped to provide gripping arms and having an attaching tongue secured to the end of the body, terminals carried by said block and each having gripping arms extending longitudinally of the block in spaced relation to each other, a cap member for fitting against said body, and terminals carried by said cap and having arm portions for extending through the block into the passages of said body and having engagement with the terminals of the block and movable into engagement with the terminals of the body when the block is rotated in one direction.

SHELBY N. GRIFFITH.
